CLAIM

The ornamental design for a display screen with icon for a
building controller lock screen, as shown and described.

DESCRIPTION

The file of this patent contains at least one drawing/photograph
executed in color. Copies of this patent with color
drawing(s)/photograph(s) will be provided by the office
upon request and payment of the necessary fee.

FIG. 1 is a first embodiment of a display screen with icon for a
building controller lock screen; and,

FIG. 2 is a second embodiment thereof.

The broken lines showing the display screen form no part of
the claimed design. The dotted broken lines showing portions
of the icon form no part of the claimed design.
